UNITED STATES PATENT OFFICE.

ANDREW J. TEWKSBURY, OF HAVERHILL, MASSACHUSETTS.

WOODEN-SOLED SHOE.

SPECIFICATION forming part of Letters Patent No. 315,572, dated April 14, 1885.

Application filed November 10, 1884. (No model.)

To all whom it may concern:

Be it known that I, ANDREW J. TEWKSBURY, of Haverhill, county of Essex, State of Massachusetts, have invented an Improvement 5 in Wooden-Soled Shoes, of which the following description, in connection with the accompanying drawings, is a specification, like letters on the drawings representing like parts.

This invention relates to the class of boots 10 and shoes commonly called "wooden-soled" shoes, to be used by miners and others, and has for its object to produce a shoe whereby ease and comfort to the wearer are attained, as well as strength, durability, and cheapness.

15 The invention is shown in this instance as applied to a brogan shoe; and it consists, essentially, in providing an upper with a bottom composed entirely of one piece; and of such peculiar shape as to provide a bearing for the 20 fore part of the foot back of the ball, or between the shank and ball; also, in other details of construction, to be hereinafter specifically described.

Figure 1 is a side elevation of a shoe embodying my invention; Fig. 2, a cross-section thereof on the line *xx*. Fig. 3 is a detail to be referred to, and Fig. 4 is a cross-section on line *yy*, Fig. 1.

The vamp *A*, quarter *B*, and stiffener *C* are 30 cut from usual patterns to form a brogan shoe. The quarter *B* at its heel portion has a V-shaped piece cut therefrom, as at *a*, Fig. 3. To the outside of this quarter *B* a stiffener, *C*, of usual shape and material, is partially stitched—35 as, for instance, from the commencement-point to the point marked 2. The edges formed at *a* are then brought together and the stitching completed. By this means a curve is produced at the heel portion of the shoe which more 40 nearly conforms to the heel of the wearer and prevents slipping.

Heretofore in brogan shoes it has been customary to unite the vamp and quarter by a lap-seam stayed by a single rivet; but in practice 45 this produces a rigid seam, besides leaving the edge of the vamp free to rub against the foot of the wearer.

In accordance with this invention the vamp *A*, suitably crimped, and quarter *B* are united 50 by means of a side seam, *b*, on the outside thereof, which is stayed at top by suitable rivets, 34, passing through the vamp and quarter and

joined together on the outside by a compound or double washer, 5, this side seam, when properly rubbed down, leaving the inner surface 55 smooth and free from the objections referred to.

The sole or bottom piece, *D*, made preferably of wood turned on an ordinary lathe, comprises in one piece what are usually termed the "outer sole," "inner sole," and "heel" of an 60 ordinary shoe.

To provide for the flexibility obtained in an ordinary boot or shoe wherein a leather sole is employed, and to produce a shoe that may conform to the movement of the foot, and also obviate slipping of the shoe at the heel, I have so shaped the sole *D* as to form a bearing-point, *f*, for the foot between the shank and ball, as shown in Fig. 1, and from that point to the toe the sole is curved. Moving the bearing-point 70 from the ball back to a point between the shank and ball also obviates the necessity of the wearer lifting the heel in walking by a strain on the foot, which is very tiresome—as, for instance, the wearer naturally first striking on the heel 75 and then the ball, the intermediate bearing-point will facilitate raising the heel, thus causing no strain to come upon the foot. The sole *D* is provided with a heel-tip, *h*, and a toe-tip, *i*, both attached thereto by means of screws 80 or nails or other suitable fastenings, and suitable stay-bolts, *g*, inserted through the ball of the sole and near the breast of the heel, prevent splitting or other accidental injury to the sole and increase its durability. This sole *D* is 85 also recessed or hollowed out to form the usual shank portion, and is rabbeted entirely around its upper edge, as at *c*.

To unite the upper and sole together, the sole is placed upon a suitable jack. The upper is then placed thereon. The edges of the vamp and quarter are placed in the rabbeted portion. A welt-strip, *d*, is also placed in the rabbeted portion against the upper, extending around the fore part and back as far as the 95 stiffener *C*, and nails or other suitable fastenings are driven through the said welt-strip and upper into the sole *D*, transversely thereto.

The welt *d* serves to increase the holding-power of the fastenings and aids in making the 100 shoe water-tight, and the rabbeted portion is preferably cut of sufficient depth to allow the welt *d* to lie flush with the edge of the sole *D*.

The sole is provided with a slight depression

or recess, as shown at *m*, Fig. 4, to receive the joint of the toe, and thus afford a proper bearing for the foot without producing too great pressure on the said joint, thus making the 5 shoe much more comfortable than it otherwise would be and enabling the shoe to be worn a long time without fatigue.

I do not desire to limit my invention to wooden-soled shoes, as some of the features 10 herein described are equally applicable to shoes of ordinary construction.

If desired, a sock-sole of any suitable material may be employed.

I claim—

In a boot or shoe, the combination, with an 15 upper, of a sole attached thereto, provided with a bearing-point, *f*, back of the ball and between the shank and ball, as shown, and for the purpose set forth.

In testimony whereof I have signed my name 20 to this specification in the presence of two subscribing witnesses.

ANDREW J. TEWKSBURY.
